(57) **CLAIM**

The ornamental design for a frame for wheeled, manually moveable pressure washer, as shown and described.

DESCRIPTION

FIG. 1 is an elevated perspective view of a frame for wheeled, manually moveable pressure washer showing my new design; FIG. 2 is a right side elevational view thereof, the left side elevational view being a mirror image thereof; FIG. 3 is a front elevational view thereof; FIG. 4 is a rear elevational view thereof; FIG. 5 is a top plan view thereof; and, FIG. 6 is a bottom plan view thereof. Environmental structures forming no part of the claimed subject matter are depicted in dashed line.
